FACEPLATE

Walter R. Schlage, Burlingame, Calif., assignor to
 Schlage Lock Company, San Francisco, Calif.,
 a corporation of California

Application February 17, 1941, Serial No. 379,186

6 Claims. (Cl. 292—337)

This invention relates to door locks, and especially to a face plate for use in conjunction with the latch bolt housing of a door lock.

There are a number of different types of door lock which are mounted or applied to a door by the simple expedient of drilling two holes therein, one longitudinally through the edge of the door parallel to the opposite faces of the door and the other at right angles thereto, or crosswise through the opposite faces of the door. In the first hole is inserted a latch bolt housing containing a latch bolt and associated retracting mechanism, and in the second is inserted a spindle housing containing a spindle and rollback mechanism. In most instances the latch bolt housing is secured or anchored against removal by the spindle housing, as it passes through the latch bolt housing, but even so the latch bolt housing is provided with a permanently secured face plate at its outer end which is fixed to the edge of the door by screws which further secures it against removal. When the latch bolt housing is anchored by the spindle housing, the face plate at the outer end could be entirely eliminated, but it is employed nevertheless because it lends a finish or ornamental appearance to which the public has become accustomed.

The object of the present invention is generally to improve and simplify the construction and operation of face plates of the character described; to provide a face plate which can be permanently or detachably secured to the outer end of a latch bolt housing; to provide a face plate which will frictionally secure the latch bolt housing when inserted in a door until permanently secured by insertion of the spindle housing; to provide a face plate which requires no screws or similar means to secure it in place; and further, to provide a face plate which is simple and cheap to manufacture, which may be quickly and readily applied, and which may be formed by punch and die operation from any suitable metal such as sheet brass, steel or otherwise.

The invention is shown by way of illustration in the accompanying drawings, in which

Fig. 1 is a perspective view of a portion of a door, showing a latch bolt housing having a face plate secured on its outer end in a position where it is partially inserted in the door;

Fig. 2 is a similar view showing the latch bolt housing full inserted and the face plate engaging the outer edge of the door;

Fig. 3 is a perspective view of the outer end of the latch bolt housing shown in Fig. 1, with the face plate removed;

Fig. 4 is a perspective view of a collar which cooperates with the face plate shown in Figs. 1 and 2;

Fig. 5 is a perspective view showing the rear side of the face plate shown in Figs. 1 and 2;

Fig. 6 is a horizontal section taken on line VI—VI of Fig. 2;

Fig. 7 is a horizontal section similar to Fig. 6 showing a modified form of face plate illustrated in Fig. 9;

Fig. 8 is a perspective view of the outer end of a latch bolt housing, showing the outer end flanged to receive the face plate shown in Fig. 9;

Fig. 9 is a perspective view showing the rear side of the face plate used in conjunction with the latch bolt housing shown in Figs. 7 and 8;

Fig. 10 is a perspective view of the spindle housing;

Fig. 11 is a horizontal section showing a hollow metal door, said view also showing a door lock installed therein and the outer end of the latch bolt housing in section;

Fig. 12 is a perspective view of a portion of the door illustrated in Fig. 11 and the latch bolt housing and face plate before they are fully inserted;

Fig. 13 is a view similar to Fig. 12, showing the latch bolt housing fully inserted and the face plate engaging the outer edge of the door;

Fig. 14 is a perspective view of the face plate disclosed in Figs. 11, 12 and 13;

Fig. 15 shows a modified form of latch bolt housing prior to application of the face plate; and

Fig. 16 is a perspective view of the latch bolt housing shown in Fig. 11, said view also showing the spindle and housing extending through the latch bolt housing.

Referring to the drawings in detail and particularly to Figs. 1, 2, 10 and 16, it will be noted that a type of door lock is illustrated which may be mounted or assembled in a door by the simple expedient of boring two holes therein, one through the edge of the door parallel to the faces

2 and 3, as indicated at 4, and one at right angles or transverse thereto, as indicated at 5. Insertable in the hole 4 is a latch bolt housing generally indicated at B, and adapted to anchor the latch bolt housing against endwise removal from the hole is a spindle housing C which extends through the opposite side walls 6—6 of the latch bolt housing, and the hole 5; the spindle housing being in turn secured by a pair of escutcheon plates D—D (see Fig. 11) which are screwed on

opposite ends of the spindle housing to engage and clamp the opposite faces of the door.

When a latch bolt housing is mounted and anchored in the manner described it becomes apparent that a face plate at the outer end of the latch bolt housing will be more or less unnecessary. Such face plates are nevertheless employed, and not only that, but they are usually permanently secured to the outer end of the latch bolt housing, and in addition thereto are secured to the edge of the door by wood screws. The only excuse for employing a face plate at all is that it provides a certain amount of finish or ornamental appearance, and for that reason is demanded by the buying public. The purpose of the present invention is to provide a face plate of the character described which will not only fill the demand of finish and ornamental appearance but also will serve other purposes herein-after to be described.

Referring to Figs. 1, 2, 5, and 6, A indicates a face plate having a rectangular opening 8 formed therein to permit the latch bolt 7 to project therethrough. Formed on each side of the face plate is an arm 9, each of which is perforated as at 10. The ends of the arms are bent back on themselves to form a pair of spring fingers 11. Cooperating with the face plate shown in Figs. 1 and 5 is a collar which is provided with an annular flange 12, and a rectangular opening 14 which will register with the opening 8 (see Fig. 4). This collar is slipped over the arms 9 prior to bending or forming the spring fingers 11, and will thus be retained against removal when the fingers are bent. By referring to Figs. 3 and 6, it will be noted that the opposite sides 6-6 of the latch bolt housing adjacent the outer end thereof are punched or forced outwardly to form protrusions or detents 15, which enter the perforations 10 to retain the face plate against removal when applied.

In actual practice, if the lock is to be applied to a wooden door the holes 4 and 5 are first bored by a brace and bit or like tool, and thus are round in cross section. The latch bolt housing, on the other hand, is square or rectangular in cross section, and open spaces 4a at opposite sides of the face plate would be left if the collar shown in Fig. 4 were not employed. Hence, before the latch bolt housing is inserted in the hole 4 the face plate is first slipped over the outer end. In doing so, the arms 9 will snap over the detents 15 and the face plate and collar will be secured and will limit inward movement of the latch bolt housing when inserted. The face plate A, together with the collar, will completely close the outer end of the hole with the exception of the opening 8 through which the latch bolt extends, and the finish and ornamental appearance required is thus obtained.

The collar should be of the same diameter as the hole, so as to center the latch bolt housing therein, but even though the hole should be over size, the spring fingers 11 will center it, and not only that, but will hold the outer end of the housing against rattling, and will cushion it. Also, the spring fingers will frictionally hold the latch bolt housing against both rotation and end-wise movement in the hole until it is finally anchored and secured in place by the spindle housing and the escutcheon plates.

The form of face plate shown in Figs. 1 to 5 is known as a detachable form, as it is held only by the detents and spring arms, and as such may be quickly and readily removed if a change is

desirable. The face plate may also be permanently secured at the end of the latch bolt housing, for instance, by the structure shown in Figs. 7, 8 and 9. In this structure, the outer end of the latch bolt housing is provided with two side flanges 16-16. The face plate proper (see Fig. 9) is provided with two side extensions 17 to receive the flanges 16, and the face plate is also provided with a series of spring fingers 18. The face plate is applied to the end of the housing shown in Fig. 8, and the sides are then crimped or indented, as shown at 19, to permanently secure the face plate to the projecting flanges 16. This plate will have all the advantages of the plate shown in Figs. 1 to 5, with the exception of detachability.

In Figs. 11 to 14, the latch bolt housing is shown as mounted on a hollow metal door and a square or rectangular hole 25 is formed in the edge 26 to receive the latch bolt housing. The face plate need only be slightly modified to be applicable. By referring to Fig. 14, two side arms 27 are formed on opposite sides of the face plate, and they are perforated as at 28 to receive the protrusions 29 formed on opposite sides of the latch bolt housing. The arms may have a spring action so as to snap over the protrusions, or the protrusions may be made sufficiently long to permit them to be clenched over the side arms as shown at 28 (see Fig. 12), if it is desirable to have the face plates permanently secured. Thus the modified form of the face plate may be detachable or permanently secured if desired.

In Fig. 15, a modified form of latch bolt housing is shown. That is, the upper and lower edges of the housing are longitudinally ribbed to stiffen and reinforce the housing and to form guideways; such ribbing of the housing does not interfere with the application of the face plate, nor do the ribs show when the face plate is applied, as the outer ends of the ribs will be covered by the upper and lower portions 30 and 31 of the face plate.

From the foregoing description, it should be apparent that the face plate, whether employed in conjunction with doors constructed of wood or metal, may be detachably or permanently secured to the outer end of the latch bolt housing. It may be made from comparatively thin sheet metal, either brass, steel, or other metal, by punch and die operations, and as such can be cheaply manufactured.

While certain features of the invention have been more or less specifically described for purposes of illustration, it is to be understood that various changes may be resorted to, all within the scope of the appended claims.

Having thus described and illustrated my invention, what I claim and desire to secure by Letters Patent is:

1. A device of the character described comprising a face plate having an opening formed therein to receive and guide a latch bolt, a pair of arms formed one on each side of the plate and extending rearwardly therefrom, a flexible finger on each arm, and a collar supported by the arms and engageable with the rear face of the face plate.

2. A face plate for latch bolt housings which are insertable in a hole drilled in the edge of a door comprising a face plate for the outer end of the latch bolt housing, a pair of projections on the exterior of the latch bolt housing, one on each side thereof, and a pair of resilient arms on the face plate insertable in the hole in the door

and disposed between the inner surface of the hole and exterior of the latch bolt housing, said arms having retaining means to snap over and engage the projections on the latch bolt housing to secure the face plate against removal.

3. A face plate for latch bolt housings which are insertable in a hole drilled in the edge of a door comprising a face plate for the outer end of the latch bolt housing, a pair of projections on the exterior of the latch bolt housing, one on each side thereof, and a pair of resilient arms on the face plate insertable in the hole in the door and disposed between the inner surface of the hole and exterior of the latch bolt housing, said arms having retaining means to snap over and engage the projections on the latch bolt housing to secure the face plate against removal, and a resilient finger on each arm engageable with the inner face of the hole which is drilled in the door to center the latch bolt housing within the hole.

4. A face plate for latch bolt housings which are insertable in a hole drilled in the edge of a door comprising a face plate for the outer end of the latch bolt housing, a pair of projections on the exterior of the latch bolt housing, one on each side thereof, and a pair of resilient arms on the face plate insertable in the hole in the

door and disposed between the inner surface of the hole and exterior of the latch bolt housing, and perforations in the arms adapted to receive the projections on the opposite sides of the latch bolt housing to secure the face plate against removal.

5. A face plate for latch bolt housings which are insertable in a hole drilled in the edge of a door comprising a face plate for the outer end of the housing, and a pair of arms formed one on each side of the face plate and engageable with the exterior surface of the latch bolt housing, said arms being bent back on themselves to form a flexible finger on each arm, and said fingers engaging the inner surface of the hole drilled in the door to frictionally secure the face plate against removal.

20 6. A face plate for latch bolt housings which
are insertable in a hole drilled in the edge of a
door, comprising a face plate for the outer end
of the housing, a pair of flexible arms formed one
on each side of the face plate and engageable
with the exterior surface of the latch bolt hous-
ing, a retaining member on each side of the latch
bolt housing and means on the flexible arms en-
gageable with the retaining members to secure
the face plate against removal.

WALTER R. SCHLAGE.
